STABILIZER FOR FIREARMS

Louis F. Landwehr, Jefferson City, Mo.

Application January 23, 1953, Serial No. 332,897

7 Claims. (Cl. 42—75)

This invention pertains to stabilizers such as are used on rifles in the practice known as bench shooting in which the rifle is supported on a fixed support and fired successively from such fixed position, the score being counted according to the scattering of the shots, rather than according to their placement upon the target.

One of the objects of this invention is to provide a stabilizer having supports for the rifle barrel, which may be adjusted to engage the barrel with any desired pressure.

Another object is to provide such a device with an indicator whereby the amount of such pressure may be noted.

Another object is to provide means for equalizing the pressure on a plurality of supports engaging the barrel, and to make such equalization automatic.

Further objects will appear in the following description taken in connection with the accompanying drawing, showing a preferred embodiment of this invention, in which—

Figure 1 is a side view of a rifle equipped with a stabilizer embodying this invention;

Figure 2 is an enlarged plan view of the stabilizer mounting;

Figure 3 is an enlarged section on line 3—3 of Figure 1;

Figure 4 is a detailed section somewhat enlarged on line 4—4 of Figure 3; and

Figure 5 is a view similar to Figure 3, illustrating another embodiment of this invention.

Fig. 6 is a view similar to Fig. 5 showing another embodiment of the invention.

Referring now to the drawing, 5 designates the rifle barrel, and 6 the stock which supports it. These may be of any usual construction, ordinarily of the type used for bench shooting. In accordance with the preferred embodiment illustrated in Figures 2 to 4, the stabilizer comprises a base 7 which may be set into a suitable recess in the forward end of the stock 6. The base 7 may be constructed of any suitable metal. Aluminum has been found very satisfactory. The base 7 is formed with a plurality of cylinders 8 adapted to contain hydraulic fluid. As shown in Figure 3, these cylinders are positioned so that their axes intersect substantially in the center line of the bore of the barrel 5. The angle between these axes is usually about 120°, although this may vary. Movable mounted in the cylinders 8 are pistons 9. These may be equipped with packing rings 10.

The pistons 9 may be arranged to abut directly against the barrel 5, the piston heads providing abutments for supporting and stabilizing the barrel. However, it has been found advantageous to provide separate abutments 11 between the pistons and the barrel. These abutments are preferably constructed of a slightly yieldable material such as nylon which is not permanently deformed by the shock of discharge of the rifle but is yet substantially rigid for support of the barrel.

In order to equalize the hydraulic pressure in the two cylinders 8, a passage 12 is formed in the base 7 connecting said cylinders. A third cylinder 13 is formed in the base 7 so as to connect with the cylinder 8 by a passage

2

12'. A piston 14 in this cylinder is arranged to be moved by a thumb screw 15 so that by movement of the piston 14, the pressure of the hydraulic fluid in the passage 12 and the cylinders 8 may be adjusted. In order that this pressure may be noted, a pressure gauge 16 is mounted so as to be readable outside of the stock 6 and communicating with the cylinders 8 and the passage 12. A filling duct 17 may be provided for supplying the pistons 8 and the passage 12 with hydraulic fluid. This duct 10 may be closed by a screw plug 18.

With the structure so far described, the barrel 5 which is secured at its breech to the stock 6 is additionally supported at an intermediate point of its length by the pistons 9, which in turn are supported by the hydraulic fluid 15 in the cylinders 8. The pistons may be caused to exert any desired pressure on the barrel 5. This is done by manipulating the screw 15 to move the piston 14 inward or outward to obtain the desired adjustment of pressure. Such pressure is indicated at the gauge 16 so that the operator may know what that pressure is and may make a record of it, if desired. It will be noted that by the action of the equalizing passage 12, the pressure in the two cylinders 8 is always the same. Accordingly, if the stock 6 should warp so as to tend to move to one side 20 or the other with respect to the barrel 5, such movement is accommodated by a corresponding shift of the pistons 9, while their pressure on the barrel is maintained constant and equal. Since the hydraulic fluid is substantially non-compressible, it provides a rigid support to receive the shock of the discharge of the rifle. Furthermore, if such shock should be delivered unequally to the two pistons 9, each would still provide a substantially rigid support, as such shock is ordinarily too sudden to permit an instantaneous equalization of pressure between the two cylinders 8 by a flow of the hydraulic fluid through the passage 12. Accordingly, while said passage permits a relatively gradual equalization of those pressures, the fluid offers a substantially rigid support to the sudden shock of the explosion.

As some bench shooters may desire to support the barrel 5 at more than two points so as to prevent shifting in any direction, the embodiment of Figure 4 provides for such support. In this case, the base 20 is provided with extensions 21 in which are mounted thumb screws 45 22 provided with abutments 23 engaging the barrel 5 above its horizontal center line. The base 20 is also provided with cylinders 24 in which pistons 25 are movably mounted and provided with abutments 26 engaging the barrel 5. The cross passage 27 connects the two cylinders 24 in substantially the same manner that the passage 12 connects the cylinders 8. In this embodiment also a gauge 16 is connected to indicate the pressure in the passage 27. For adjusting the pressure in the cylinders 24, a third cylinder 28 is provided with a piston 29 operated by a thumb screw 30. Thus, by adjusting the screw 30, the piston 29 may be moved to adjust the pressure in the passage 27 and the cylinders 24.

In the embodiment of Figure 4, one or more valves 31 may be provided in the passage 27 so as to control the flow of fluid between the cylinders 24. These valves may or may not be used as desired. They may be adjusted by means of screws 32 to a more or less completely closed position, forming thereby a restriction in the passage 27 to control the rate of flow of the hydraulic fluid through said passage. These valves may be used in two ways. They may be closed during the firing of the rifle so that the hydraulic fluid is locked in the cylinders 24 to provide rigid support for the barrel, and they may be opened between firings so as to permit readjustment of the pressure. Alternatively, they may be left open and one or both of them adjusted to provide a restriction in the passage of flow.

It will be clearly noted that if desired, the screws 22 may be replaced by hydraulic pistons such as 25 by suitable modifications of the base 20. Connecting passages, such as 27, may be provided to equalize the pressure in all cylinders, and valves, such as 31, may be placed at such points as to restrict or cut off the flow of such fluid where desired. For example, the base 20 might be provided, in place of the upward extensions of the members 21, with an upper half substantially identical with the lower half, as illustrated in Fig. 5; thereby providing a pair of pistons 25 in a relation to the barrel 5 similar to that of the screws 22. Such a modification is illustrated in Fig. 6 wherein a base section 20a, similar to the base 20, is superimposed thereon.

It will be seen that this invention provides a simple and effective means for stabilizing a rifle barrel of the type here involved. The supporting abutments may be located as desired around the circumference of the barrel, and connected by fluid passages so that the supporting pressure in all the cylinders may be equalized. Thus an equal pressure on all supports may be had. Furthermore, unequal pressure in any desired ratio may be had by varying the size of the pistons, such ratio being maintained constant at all pressures of the fluid. The fluid pressure is adjustable to any desired value, and such value is indicated on the gauge 16. This enables the operator to know exactly what pressure is used, and to keep a record of it for comparison with past or future operations.

The base 7, instead of being set into a recess of the stock as shown, may be attached at the end of the stock. This avoids the necessity of recessing the stock and makes it easier to apply different stabilizers interchangeably.

Various changes may be made in the details of construction, within the scope of the appended claims, without departing from the spirit of this invention. Parts of the invention may be used without the whole and improvements may be added while retaining some or all of the advantages of the invention.

I claim:

1. A stabilizer for a firearm having a barrel and a support therefor such as a stock, comprising, a base mounted in said support, said base having a plurality of hydraulic cylinders, pistons movable in said cylinders, abutments supported by said pistons and in supporting engagement with said barrel, said base having a passage for hydraulic fluid connecting said cylinders, and means for controlling the hydraulic pressure in said passage.

2. A stabilizer for a firearm having a barrel and a support therefor such as a stock, comprising, a base mounted in said support, said base having a plurality of hydraulic cylinders, pistons movable in said cylinders, abutments supported by said pistons and in supporting engagement with said barrel, said base having a passage for hydraulic fluid connecting said cylinders, and means for controlling the flow of fluid therein.

3. A stabilizer for a firearm having a barrel and a sup-

port therefor such as a stock, comprising, a base mounted in said support, said base having a plurality of hydraulic cylinders, pistons movable in said cylinders, abutments supported by said pistons and in supporting engagement with said barrel, said base having a passage for hydraulic fluid connecting said cylinders, and a valve in said passage adjustable to control the flow of fluid therein.

4. A stabilizer for a firearm having a barrel and a support therefor such as a stock, comprising a plurality of stabilizing means carried by said support and including abutments engaging said barrel at a plurality of points, each of said means being responsive to hydraulic pressure, a conduit carrying a liquid connecting said means whereby pressure exerted on said stabilizing means is equal, and means for controlling the pressure in said conduit.

5. A stabilizer for a firearm having a barrel and a support therefor such as a stock, comprising a plurality of stabilizing means carried by said support and including abutments engaging said barrel at a plurality of points, each of said means being responsive to hydraulic pressure, a conduit carrying a liquid connecting said means whereby pressure exerted on said stabilizing means is equal, a manually operable valve in said conduit, and means for controlling the pressure in said conduit.

6. A stabilizer for a firearm having a barrel and a support therefor such as a stock, comprising a plurality of hydraulic cylinders carried by said support, pistons movable in said cylinders, abutments supported by said pistons and in supporting engagement with said barrel, a conduit carrying a liquid connecting said cylinders whereby pressure exerted on said pistons is equal, another cylinder connected to said conduit, a piston in said other cylinder, and manually operable means for moving the piston in said other cylinder.

7. A stabilizer for a firearm having a barrel and a support therefor such as a stock, comprising a plurality of hydraulic cylinders carried by said support, pistons movable in said cylinders, abutments supported by said pistons and in supporting engagement with said barrel, a conduit carrying a liquid connecting said cylinders whereby pressure exerted on said pistons is equal, another cylinder connected to said conduit, a piston in said other cylinder, manually operable means for moving the piston in said other cylinder, and a manually operable valve in said conduit.
